UNITED STATES PATENT OFFICE.

LEONARD CHARLES HARVEY, OF MALDEN, ENGLAND.

ELECTRICALLY-HEATED MELTING-FURNACE.

1,337,839.

Specification of Letters Patent. Patented Apr. 20, 1920.

Application filed November 11, 1919. Serial No. 337,236.

To all whom it may concern:

Be it known that I, LEONARD CHARLES HARVEY, a subject of the King of Great Britain, residing at The Red House, Malden, 5 Surrey, England, have invented new and useful Improvements in Electrically-Heated Melting-Furnaces, of which the following is a specification.

My invention relates to electrically heated 10 melting furnaces of the kind wherein provision is made for continually washing the surfaces of the refractory lining with molten metal, thereby greatly reducing the power taken for melting the metal, due to the heat 15 stored in the brickwork being transmitted to the metal in this manner, and also tending to prolong the life of the lining, by preventing local overheating, a common fault with furnaces which are stationary during 20 the melting operation, and to effect a thorough mixing of the metal or alloy melted.

Heretofore it has been proposed to impart a rocking motion to the furnace in such 25 a manner that a to-and-fro movement is communicated to the molten metal, which causes it to approach the pouring or charging door on either side, without actually letting any metal escape at this door, so that 30 local overheating of the firebrick lining can therefore only take place at that part of the lining in which the pouring door is situated.

The object of my invention is to protect 35 the whole of the melting chamber lining from local overheating and to introduce at the same time other novel and valuable features.

To this end, according to my invention, I 40 construct a melting chamber, open at one end and arranged in an inclined position, to which a continuous rolling motion can be imparted, whereby the molten metal contained therein can be made to cover or wash the whole of the refractory lining in the melting or high heat zone, a heating element, held against rotation, being inserted 45 through the open end.

In practice the melting chamber is preferably made of flask form in two metal sections bolted together and lined with refractory material in the usual manner, the neck 50 part of the body being cylindrical in shape while the melting section is preferably of bulbous shape.

My invention will be readily understood

by reference to the accompanying drawing, 55 in which:—

Figure 1 is a longitudinal section of the furnace made in accordance with my invention.

Fig. 2 is an elevation illustrating a modification of a portion of the apparatus.

a indicates the body of the furnace open at one end, which is preferably made in two sections as at *b* bolted together and which is provided with refractory lining *c* an opening *d* being formed through the cylindrical or neck portion of the furnace and a spout *e* provided at this point and normally closed by the cover *f*. The melting chamber thus formed is carried in an inclined position 65 upon a frame comprising a bed-plate *g*, two bearing brackets *h* (one only of which is indicated in the drawing) having between them a saddle *i*, provided with anti-friction rollers *i*¹, on which the neck or cylindrical portion of the melting chamber is supported, and another bracket *k* having a bearing *l* in which a gudgeon *m*, secured to or formed integral with the casing *a* at the bulbous end of the melting chamber on 70 the axial line is carried, thereby allowing 75 of the melting chamber being rotated.

In practice, the inclination of the melting chamber is such that when the furnace is charged with molten metal, the level of the 85 latter will be slightly below the level of the spout, as indicated in Fig. 1.

Rotary motion can be communicated to the melting chamber by any suitable means. In the drawing, the gudgeon *m* is represented as having a worm wheel *n* fixed to it, with which a worm *o* engages, the shaft of the said worm being mounted in bearings in the bracket *k* and being driven, say, by an electric motor, indicated at *p* through the 90 medium of gear wheels *p*¹.

In the drawing, anti-friction balls *q* are represented as being arranged between the shoulder of the gudgeon *m* and the bearing *l* to take the thrust due to the portion of 100 the weight of the furnace to reduce friction.

r indicates a head which is designed to be inserted into the open end of the melting chamber *a*, and through which electrodes *s*, Fig. 1, for the formation of the electric arc, are extended. This head *r* can be inserted or withdrawn, for instance, by tackle from an overhead runway, see Fig. 1, and when in

position in the cylindrical end of the melting chamber the latter can be revolved around it, the head r being held against rotation by stops or clamps, not shown, but which can be fixed to the supporting brackets h and the electrodes are also carried and arranged in conjunction with feed mechanism, not shown.

Instead of using the electric arc for heat generation the heating element may be composed of resistance material. Such an arrangement is illustrated in Fig. 2, in which t indicates the resistance material carried upon a tubular spindle u through which the conductors are passed, and t, t' terminals for the attachment of the leads. In some cases it might be advantageous to use the head r with electrodes for heat generation by means of the electric arc and subsequently insert another head r with a heating element of resistance material or vice versa so that either one can be used, as desired, or both in the manner described. For instance, it might be found advisable to melt metal having a high melting point, with an arc element and subsequently to continue the operation, when alloying metals have been added, with the resistance element.

In order to pour the molten material, means must be provided for tipping the melting chamber a . As shown in the drawing, the base plate g is pivoted at v to a foundation plate w and a quadrantal rack x is fixed to the rear end of the base plate g with which a pinion y , carried on arms or brackets z fixed to the foundation plate m engages, so that the rotation of the said pinion by suitable means (not shown) will tip the whole structure.

It will be understood, however, that the melting chamber may be mounted in its bearings in such a manner that it can be lifted therefrom by means of suitable tackle, and used as a ladle.

During the melting operation the melting chamber is continuously rotated so that

local-overheating of the furnace lining is prevented, while the heat imparted to the lining at the point nearest to the heating element, is quickly transferred to the metal. 50

Claims.

1. An electrically heated melting furnace comprising a chamber open at one end and arranged in an inclined position, means for rotating the chamber about an inclined axis 55 which extends longitudinally through the chamber, and a heating element, held against rotation, extending through the open end of said melting chamber.

2. An electrically heated melting furnace 60 of the kind claimed in claim 1, wherein the melting chamber is in the form of a flask, the bulbous portion of the said chamber forming a metal reservoir, while the cylindrical portion of the said chamber is provided with a pouring spout and adapted to have a head carrying the heating element inserted into it, substantially as described.

3. An electrically heated melting furnace comprising a substantially cylindrical 70 shaped melting chamber having an open upper end and a closed curved bottom, means supporting the chamber in inclined position, means for rotating the chamber about an inclined axis extending longitudinally through 75 the chamber, and a heating element extending into the open end of said chamber.

4. A furnace of the kind defined by claim 3, in which a gudgeon fixed to the bottom of the chamber and extending co-axially of the 80 axis of rotation forms a part of the chamber supporting means, gearing operatively connected to said gudgeon, and means for imparting movement to the gearing to cause rotation of the chamber.

5. A furnace of the kind defined in claim 1 in which one of the side walls of the chamber is provided with a pouring spout, a platform supporting the chamber, and means for tipping the platform to pour the 85 metal from the chamber.

LEONARD CHARLES HARVEY.
